[57] ABSTRACT

A device for applying inconspicuous coded indicia, such as indicia indicating the date of production, on labels of a type applied to various products, such as canned or bottled products. The device is characterized by an ink applicator secured to a base and having adjustable ink applying elements thereon in a coded arrangement, a means connected to the base to supply ink to the ink applying elements, means to facilitate relative contacting movement between the edges of stacked labels and the ink applying elements. The ink applicator presents a profile complimentary to the profile of the label on which it is applying coded information.

FIG. 2

1
CODE LABELING DEVICE

BACKGROUND OF THE INVENTION

This invention relates generally to devices for applying codes to packages and particularly to labels which are later attached to various products. Manufacturers of a wide variety of consumer products find it desirable and necessary to indicate on their products the dates of production. This is desirable to assist, for example, in determination of whether a particular product was in a batch of defectively produced products. A dating system will remove uncertainty as to the thoroughness of a product recall and avoid the necessity of a total recall of all products regardless of production date. Date information is useful for various other reasons as will be readily appreciated. In some cases, other information is also desirable for various reasons.

In the past, various codes have been developed to indicate information on containers without revealing it to the consumer and various means have been developed to place coded indicia on a product. Various numbers according to a code might be stamped on the bottom of a container or in an inconspicuous location on a label. In some systems, scratch marks have been made on metal containers in an inconspicuous location. One widely used method of code dating various products has been cutting slits spaced according to the code on the edge of a label, such as a paper label, which is applied to a container. Such slitting of labels is of particular harm to the appearance of the label and further puts the label in condition such that tearing upon further packaging or handling is quite likely.

One disadvantage of these and other methods is that in spite of an attempt to preserve good package appearance the coding defaces the appearance to some extent. Furthermore, the methods of applying such coded information are often clumsy and undependable.

The ideal coding system would provide clearly legible coded indicia which may be applied in a dependable fashion in an inconspicuous location on the product. The coded indicia should be easy to apply and, importantly, should not detract from the package appearance. The prior methods have fallen short in one or more of these categories.

I have invented a device which applies coded indicia on labels in a manner meeting all of the aforementioned requirements. The device disclosed herein puts clearly legible coded indicia on a label in a dependable fashion. The indicia is easily applied with the device of my invention and the appearance of the package is virtually unchanged to any casual or careful observer unless he is aware of the location of such indicia.

The device of my invention applies coded indicia to the edge of labels to be thereafter applied to products. The code is applied without cutting or defacing the edge of the label in any way. My invention has the further feature of being adaptable to labels of all configurations as will be explained further herein.

My invention is based in part upon the discovery that inked indicia carefully applied to the edge of a sheet label is readily legible to the educated observer without exception. Further, the device of my invention has the ability to apply such inked indicia to stacks of labels without missing a single label, even though the indicia may be applied by unskilled labor.

2

It is the primary object of my invention to provide a device for applying coded indica to labels which overcomes the aforementioned problems.

It is a further object of my invention to provide a device for coding labels which is easy to operate and dependable.

It is another object of my invention to provide a simple device for legibly coding labels in an inconspicuous manner without detracting from the package appearance.

It is yet another object of this invention to provide a device for coding labels in bulk which has all the aforementioned advantages.

These and other important objects will become apparent from the following description and from the drawings showing preferred embodiments wherein:

FIG. 1 is a partially cutaway side elevation of the device of my invention.

FIG. 2 is a top plan view of the device of my invention.

FIG. 3 is a partially cutaway front elevation of the device shown in FIGS. 1 and 2.

FIG. 4 is a front elevational view of an ink applicator device presenting a concave periphery.

In the drawings, like parts are given the same numbers in each of the drawings. Referring specifically to FIG. 1, code dating apparatus 20 is shown having a base 22 comprising a rectangular metal plate and various other parts as indicated. Riser 24 provides a platform upon which support piece 26 is mounted. Shaft 28 turns in bearing means 30 in support piece 26. Shaft 28 is horizontally mounted.

As shown in FIGS. 1, 2, and 3, ink applicator wheel 32 is attached to shaft 28 and turns therewith. Ink applicator wheel 32 has periphery 34 which is generally cylindrical as shown in FIGS. 1, 2, and 3. Periphery 34 defines parallel annular grooves around wheel 32. As shown best in FIGS. 2 and 3, several "O" rings are wrapped about wheel 32 and secured in certain of the grooves 36. The choice of grooves relates to the code being used. O rings 38 are ink applying elements which roll against the edges of labels in a stack as will be explained further herein.

As shown in FIG. 1, riser 24 has a lateral extension 40 through which shaft 42 extends parallel to shaft 28. Affixed to shaft 42 is a roll 44 which serves as an ink supply means for the O rings. Roll 44 is preferably an ink impregnated porous substance, such as for example that sold under the trademark PORELON. As the wheel 32 and roll 44 turn, O rings 38 contact roll 44 at contact point 86 shown in FIGS. 1 and 2. Ink is removed from roll 44 to rings 38 and is later applied to the label edges as will be explained.

Slidable tray 46 is attached to base 22 through various support pieces shown in the figures. Slidable tray 46 is mounted to move in left and right directions as shown in FIGS. 1 and 2. Tray 46 includes table 48 which defines a slot 50 therein which serves as an access area for ink applicator wheel 32 to labels which are stacked with their edges down in tray 46. Side wall 52 and stack-holding piece 58 are adjustable to accommodate labels of various sizes in tray 46.

A stack of labels, such as paper labels, will be placed in tray 46 with the plane of said labels being parallel to stack-holding piece 58 and front wall 59. Side wall 52 may be adjusted along slots 56 to accommodate a particular size and shape of label. Clamp screws 54 will be

tightened to fix side wall 52 in the appropriate position, as shown best in FIG. 3. Stack-holding piece 58 will be moved to the left as shown in FIG. 2 for the loading of a stack of labels in tray 46. This position is shown by means of phantom lines in FIG. 2. After the stack is placed in tray 46 in the manner earlier described, stack-holding piece 58 will be tightened to the right. Stack-holding piece 58 is mounted on threaded shaft 60 as shown in FIGS. 1 and 2 which extends through support piece 62 and has a crank means 63 with handle 64 attached to the end thereof to facilitate tightening of a stack of labels between front wall 59 and stack-holding piece 58.

It will readily be appreciated that the edge of each of the labels in the stack will extend across access area 50 in table 48. As the tray is pushed, by hand or otherwise, to the right as shown in FIGS. 1 and 2, the edges of the labels in tray 46 will pass over ink applicator wheel 32. As such movement occurs, O rings 38 will apply ink from ink supply roll 44 to the edges of such labels. 20

As best shown in FIG. 3, the shaft support 66 is mounted on base 22 and has shaft 68 rotatably mounted therethrough on bearing means 70. Pinion gear 72 is affixed to shaft 68 in a position to mesh with rack 74 which is attached to slidable tray 46 by fasteners 76 as shown in FIG. 3. The back and forth slidable motions of tray 46 will produce rotation of pinion gear 72 and shaft 68. Secured to the other end of shaft 68 is pulley 78. Pulley 80 is secured to extension 82 of shaft 28 and is aligned with pulley 78. Belt 84 transmits the rotation of shaft 68 to shaft 28. Thus, upon the movement of tray 46, a spinning motion is imparted to ink applicator wheel 32. By reason of the contact of wheel 32 and roll 44, fresh portions of ink supply roll 44 will be presented to the portions of O rings 38 at various peripheral portions of wheel 32. The rotation of wheel 32 and its rings 38 also aids in the application of ink to the edges of the labels in tray 46. 35

Movement of the tray is preferably achieved by an operator placing his hand on the labels secured in tray 46 or by his gripping side wall 52, stack-holding piece 58, and/or front wall 59. Tray 46 is preferably made of a sufficient dimension to allow several hundred labels to be indicia marked at one time. 40

FIG. 4 shows an applicator wheel designed specially to accommodate a label having a curved edge, just as the ink applicator wheel shown in FIGS. 1, 2, and 3 is designed to accommodate labels having a straight edge. The applicator wheel may be removed from the apparatus of my invention and replaced with a wheel of a different contour simply by removing fastener 88 from shaft 28 and later securing it after replacement of an applicator wheel. 45

The code may be adjusted simply by moving the O rings to grooves of a different spacing. Codes of various types may be devised to specify dates or other information desired. The various parts of the apparatus described are preferably made of machine steel, but a wide variety of materials may be used as will readily be appreciated by those skilled in the art and familiar with the teaching of my invention. As mentioned, the ink supply means is preferably a PORELON roller. The O rings are preferably rubber rings, but other materials may be used. 55

Ink supply means other than as specifically described may be used in my invention. For example, an ink supply means could be located inside the ink applicator. A

wide variety of ink supply means would be suitable. However, I have found PORELON rolls to be most satisfactory.

While in the foregoing specification this invention has been described in relation to certain preferred embodiments thereof, and many details have been set forth for the purpose of illustration, it will be apparent to those skilled in the art that the invention is susceptible to additional embodiments and that certain of the details described herein can be varied considerably without departing from the basic principles of the invention.

I claim:

1. A device for coding package labels of the type having ink-applying elements for placing inked indicia on labels, said device comprising:

a base;

means attached to said base for gripping a stack of labels, said means including clamp elements defining parallel planes of stack contact to orient a stack of labels surface-to-surface with evenly aligned edges, said means defining an access opening therealong through which a tight, flat surface of edges may be exposed;

means attached to said base for holding said ink-applying elements at said access opening, said holding means having a plurality of holding locations spaced along its length, across said access opening, for said ink-applying elements;

a lesser plurality of said ink-applying elements arranged along substantially the entire length of said holding means at certain of said holding locations according to code, each of said ink-applying elements secured at one of said holding locations, said ink-applying elements being across said access opening;

an ink impregnated ink supply structure mounted to said base in position to contact said ink-applying elements to supply ink thereto;

means to facilitate relative movement of said ink-applying elements in contact with said ink supply structure; and

means to facilitate relative movement of said stack gripping means with respect to said ink-applying elements, said relative movement being in a direction transverse said planes and said edges,

whereby labels may be marked with coded indicia which are clearly discernible to those aware of their presence yet are inconspicuous to those unaware of their presence. 50

2. The device of claim 1 wherein said means for holding said ink-applying elements comprises a rotatably mounted wheel.

3. The device of claim 2 wherein said wheel defines axially spaced annular grooves around the periphery thereof to form said holding locations and wherein said ink-applying elements comprise O rings around said wheel in certain of said grooves, said O rings being in contact with said ink supply structure. 55

4. The device of claim 3 wherein said wheel has a curved profile to complement stacked labels having curved edges.

5. The device of claim 3 wherein said ink supply structure is a generally cylindrical roll in peripheral contact with said O rings.

6. The device of claim 1 wherein said stack gripping means is a slidable tray, said tray defining said access

opening, said access opening extending along said tray in the direction of slidable motion, and said ink-applying elements being across said access opening.

7. The device of claim 6 wherein said means for holding said ink-applying elements comprises a rotatably mounted wheel.

8. The device of claim 7 wherein said wheel has axially spaced grooves around the periphery thereof to form said holding locations and wherein said ink-applying elements comprise O rings around said wheel in certain of said grooves, said O rings being in contact

with said ink supply structure.

9. The device of claim 8 wherein said ink supply structure is a generally cylindrical roll in peripheral contact with said O rings.

10. The device of claim 9 including mechanical linkage linking said slidable tray, said wheel and said ink supply roll, whereby said ink supply roll peripherally and rotatably engages said O rings on said wheel and said wheel rotates to apply ink to edges of labels in said tray.
